UNITED STATES PATENT OFFICE

WILLARD F. RICHARDS, OF DEPEW, NEW YORK, ASSIGNOR TO THE SYMINGTON COMPANY, OF NEW YORK, N. Y., A CORPORATION OF MARYLAND

SIDE FRAME AND JOURNAL BOX

Application filed February 15, 1927. Serial No. 168,338.

This invention relates to side frames for railway trucks and, more particularly, to such frames of the type in which each journal box comprises a portion formed integral with or 5 rigidly connected to the side frame and a movable portion which can be opened or moved into inoperative position with respect to said rigid portion.

The principal object of my invention, generally considered, is to provide a truck side frame with journal boxes associated therewith, each journal box comprising upper and lower portions resiliently held together.

An object of my invention is the provision 15 of a cast steel side frame formed with the upper portion or top half of each journal box cast integral therewith and the lower portion or bottom half pivotally mounted with respect to the frame and means provided for 20 resiliently holding the free side of said pivoted portion of the journal box against the corresponding portion of the upper part thereof.

Another object of my invention is the provision 25 of a journal box in which the lower portion thereof is relatively shallow or closely spaced with respect to an associated journal for bringing and holding lubricating material close to said journal for properly lubricating the same.

A further object of my invention is the provision 30 of a journal box formed with ribs preferably positioned one on either side of an associated journal and extended inwardly and sloped downwardly to adjacent said journal for preventing the waste or other lubricating material from creeping up and causing overheating due to lubricating material binding between the journal and its bearing.

40 A still further object of my invention is the provision of a journal box in which the bottom thereof is coaxial with the associated journal, thereby keeping the waste or lubricating material from settling down away from the journal.

An additional object of my invention is the provision 45 of a journal box formed in two parts, the upper part thereof being integrally or rigidly connected with an associated frame and the lower part being resiliently

held to said frame and pressed upwardly against the upper part to constantly hold lubricating means therein in place against an associated journal regardless of the wear thereof.

55 Other objects and advantages of the invention relating to the particular arrangement and combination of the various parts will become more apparent as the description proceeds.

60 Referring to the drawings illustrating my invention, the scope whereof is defined by the appended claims:

Figure 1 is a side elevation of one half of a side frame and associated journal box embodying my invention.

Figure 14 is a fragmentary end elevation corresponding to Figure 8 but showing a still further modification of my invention.

Figure 15 is a fragmentary vertical sectional view on the line 15—15 of Figure 14 looking in the direction of the arrows.

Figure 16 is a fragmentary vertical sectional view on the line 16—16 of Figure 17 looking in the direction of the arrows and showing an additional embodiment of my invention.

Figure 17 is a fragmentary end elevation looking from the left at the construction illustrated in Figure 16.

Referring to the drawings in detail, and first considering the embodiment of my invention illustrated in Figures 1 to 7, inclusive, like parts being designated by like reference characters, I have shown a side frame 1 which may be of generally conventional construction and comprise a compression member 2 and a tension member 3 spaced at intermediate portions thereof by bolster guide column or strut portions 4. These members 5 may be generally U shape in cross section or of other desired configuration.

In the present embodiment of my invention, the frame is provided with a journal box 5 at each end thereof, said journal box 30 being formed in two sections or halves, an upper section 6 and a lower section 7. Although in Figure 1 only one half of the side frame and associated boxes are shown yet it will be understood that the frame is symmetrical and a box is provided at each end thereof. Although in the present embodiment the upper portion or half 6 of the journal box is shown integral with the adjacent part of the side frame yet, as will be understood, it may, 40 if desired, be formed separately and rigidly or otherwise connected to the side frame in any desired manner, for example, as shown in the Patent No. 1,585,522 of May 18, 1926, to Donald S. Barrows entitled Journal box 45 fastening means.

The upper or integral portion 6 of the journal box 5 may be of generally conventional interior construction and provided with the usual brass lugs 8. The dust guard wall 50 or pocket 9, however, may be formed without the usual upper opening for reasons to be hereinafter explained more in detail. The side frame may be extended entirely over the roof or top wall of the journal box 5 and 55 continued down over the outer wall, as indicated at 10, terminating in a flange or web 11 between the side walls thereof, to define a pocket 12 adapted for receiving resilient means 13 for holding the lower part 7 of the 60 journal box in proper position against the upper part 6. The inner side wall 14 of the journal box may be rigidified and connected with the adjacent portion of the tension member by a pair of longitudinally extending 65 webs or triangular gusset portions 15. These

webs are, in the present embodiment, provided with registering apertures 16 and inwardly extending bosses 17 around said apertures for increasing the bearing area therein.

The lower or movable portion 7 of the journal box 5 is preferably pivotally connected with respect to the upper portion 6 of said journal box by a bolt or the like 18 extending through registering apertures in a pair of hinging lugs or ears 19, preferably integral with said lower portion 7, and the apertures 16 in the webs 15 heretofore referred to. Said bolt may be headed at one end and the other end provided with a nut 20 and locking device 21 for preventing loss 80 of said nut. The lower portion 7 of the journal box is adapted to telescopically or interlocking engage the upper portion 6 thereof and, for that purpose, has its side walls continued so that they normally extend above 85 the lower edge of the side walls of the upper portion 6 and are adapted to eventually engage abutments 22 on said side walls. The free edge or side of the movable portion 7 of the journal box is formed with an outstanding flange or lip 23 perforated for the reception of the bolt or pin portion 24 of the resilient means 13. Said resilient means 13, in the present embodiment, is shown as comprising the bolt 24 provided with a head 25 at its 90 upper end and a coil or helical spring 26 surrounding said bolt and positioned between the web 11 of the frame and the head 25 of the bolt to thereby resiliently urge said bolt upwardly. The lower end of said bolt 24 100 extends through the perforated lip 23 on the lower portion 7 of the journal box and is threaded for the application of a nut 27 thereon. Said nut may be formed with lugs 28 adapted to engage corresponding grooves 105 in the seat of the lip 23 for preventing undesired rotation thereof.

In the present embodiment, the lower portion of the pivoted section 7 of the journal box is curved beneath the associated journal 29 coaxially with respect thereto so that waste or other lubricating material between the same and the journal is kept in operative engagement with said journal and prevented from settling away from the same as has happened 110 with other forms of journal boxes. Extending inwardly from the sides of the lower portion 7 of the journal box are ribs or flanges 30 which preferably continue to almost engage 115 the associated journal 29, the inner portions thereof sloping downwardly to prevent oily waste or other lubricating material from creeping up around the journal and binding, thereby obviating undue heating. The sloping of the ribs 30 downwardly and inwardly 120 also serves to drain oil back to the lower portion of the journal box. From a consideration of Figure 6, particularly, it will be seen that the flanges or ribs 30 are curved at 125

their ends, as indicated at 31, to conform with the shape of the journal.

Positioned between said journal 29 and the top of the journal box 5 are a brass 32 and a wedge 33 which may be of conventional form. The upper surfaces of the ribs 30 are normally spaced from the lower surfaces of the side walls of the upper portion 6 of the journal box a distance corresponding with the spacing between the stop portions 22 and the top of the movable portion 7 of the journal box thereby allowing a desired amount of upward movement upon wearing of the journal and brass. This upward movement is automatically effected by the spring 26 pulling up on the bolt 24, the nut 27 and free side of the pivoted portion 7 of the journal box, whereby said pivoted portion and the contained lubricating material is constantly held in place against the journal regardless of wear.

The dust guard well or pocket 9 is formed in two parts, that is, the top portion thereof is provided in the rigid part 6 of the journal box and the bottom portion is formed in the movable or swinging part 7 thereof. Any desired dust guard may be positioned in said pocket but, in accordance with the present embodiment of my invention, I propose a two part dust guard 34, both of said parts, however, being interchangeable and similarly formed if desired. Each part 35 may comprise a semi-circular preferably metallic collar portion 36 preferably U shape in cross section as shown particularly in Figure 5. The ends of said collar portions are bent away from each other as indicated at 37 and both of said semi-circular collars are advantageously lined with felt or other similar material 38, the ends of said felt sections being riveted or otherwise connected to the free ends 37 of the collars 36 as indicated particularly at 39. For urging said collar sections and particularly the felt lining thereon into operative engagement with the journal 29, bent leaf springs 40 are provided, advantageously connected with the collar portions 36 by rivets or the like 41 and formed at their ends with curved portions 42 respectively engaging the top and bottom walls of the journal box 5 whereby the same are urged together and into operative engagement with the journal thereby effectively sealing the inner opening 43 of the journal box. On account of the lower portion of the journal box being made movable downwardly, the dust guard may be inserted upwardly into place before the lower portion of the journal box is moved into position thereby obviating the necessity of providing the usual top opening above the dust guard well.

The outer opening 44 in the journal box may, if desired, be formed entirely in the upper or rigid section thereof, and, in the present embodiment, is shown closed by a lid 45 pivoted to a journal box hinge lug 46 by

means of a hinge pin or pintle 47 extending through an aperture in said lug and corresponding registering apertures in the hinge ears 48 of the lid. A flat spring 49 riveted or otherwise suitably connected to the lid at 50 is shown which is adapted to hold the lid in either open or closed positions by engaging suitable angularly disposed faces on the lug 46 in a well understood manner. The lower edge 51 of the lid is disposed so as to overlap the upper edge of the pivoted portion 7 of the journal box and form a tight seal therewith. A usual form of lip 52 may be provided on the lower edge of the lid for convenient manipulation thereof.

Although I have shown the movable portion 7 of each journal box as a casting yet it is to be understood that my invention is not limited to such construction for, if desired, said portion may be formed of pressed metal as it merely serves for housing the lubricating material and is not normally subjected to excessive strains or shocks in service.

Referring now to the embodiment of my invention illustrated in Figures 8 and 9, I have shown an end portion of a side frame 1^a provided with a journal box 5^a, said journal box being formed, as in the previous embodiment, in two sections or halves, an upper section 6^a and a lower section 7^a. In the present embodiment, the upper section of the journal box is shown integral with the adjacent part of the frame but, as previously explained, I do not wish to be limited to such construction.

The upper or integral portion 6^a of the journal box may be of generally conventional construction and correspond substantially to that shown in the first embodiment except that, if desired, the roof may be formed with sloping end portions 53, as illustrated. The side frame is preferably extended entirely over the roof or top wall of the journal box 5^a and continued down over the end wall as indicated at 10^a, tapering to finally merge with said end wall, as illustrated. A flange or web 11^a is preferably formed between the side walls of the side frame 1^a providing a pocket 12^a adapted to receive resilient means 13^a for holding the lower part 7^a of the journal box in proper position against the upper part 6^a. The inner side wall 14^a of the journal box may be rigidified and connected with the adjacent portion of the tension member of the side frame by longitudinally extending webs or triangular gusset portions 15^a. These webs, as in the preceding embodiment, are preferably provided with registering apertures receiving a bolt or other pivoting means 18^a for movably mounting the lower portion 7^a of the journal box 5^a with respect to the side frame 1^a, said pivotal means 18^a preferably extending through hinging lugs or ears 19^a desirably formed integral with the movable portion of the journal box as in the preceding embodiment.

The lower portion 7^a of the journal box is adapted to telescopically or interlockingly engage the upper portion 6^a thereof and, for that purpose, has its side walls continued so that they normally extend above the lower edge of the side walls of the upper portion 6^a and are adapted to engage abutments 22^a on said side walls. Extending inwardly from the sides of the lower portion 7^a of the journal box are ribs or flanges 30^a which preferably continue to almost engage the associated journal 29^a, diagrammatically illustrated, as in the previous embodiment for a similar purpose. Extending upwardly from intermediate portions of said ribs 30^a are flanges 54 which lie inside of the side wall portions of the upper half 6^a of the journal box and, together with the upper portions of the side walls of the movable half 7^a, form pockets 55 which telescopically receive the lower edge of the fixed portion 6^a of the journal box. Deflecting ribs or flanges 56 are preferably provided on the fixed portion 6^a of the box extending downwardly and inwardly over the flanges 54, as illustrated.

The free edge or side of the movable portion 7^a of the journal box is, in the present embodiment, formed with outstanding lugs or ears 23^a perforated for the reception of a bolt or pin 24^a. Said bolt is adapted for engagement with the resilient means 13^a, hereinbefore referred to, and particularly with the keeper or perforated head portion 25^a thereof. Extending upwardly from the keeper portion 25^a is a threaded extension or bolt portion 57 extending through an aperture in the web 11^a, surrounded by a helical spring or other resilient means 26^a and supplied with a nut 27^a at its upper end. The side walls of the side frame, adjacent the nut 27^a, are preferably provided with inward extensions 58 which come so close to the nut 27^a that they prevent appreciable turning thereof and thereby lock the same in position after assembly.

A preferred method of assembling the movable portion 7^a of the journal box with the frame and rigid portion thereof is as follows. The pivot bolt or pin 18^a is inserted 50 to mount said movable portion 7^a with respect to the frame 1^a as in the previous embodiment. The resilient means 13^a is then connected to the frame by first inserting the extension or bolt portion 57 through the apertured web 11^a of the frame, applying the spring 26^a thereof and the nut 27^a thereon, said nut being tightened to the requisite degree by turning the keeper or head portion 25^a rather than by turning the nut, said nut 55 being held in position between the extensions 58 of the frame. It will be noted that the keeper or head portion 25^a is formed with an aperture 59 adjacent its lower end and the free edge of the movable portion 7^a of the box is formed with a corresponding pocket or

indentation 60, the purpose of which is to facilitate insertion of the bolt 24^a. The movable portion 7^a of the lid, after filling the same with waste or other lubricating material, is swung to the position indicated in Figure 9, and a bar, piece of pipe or other lever means 61 inserted through the aperture 59 into the pocket 60 whereby sufficient leverage is obtained to compress the spring 26^a until the transverse aperture in the keeper 25^a is alined with the corresponding apertures in the ears 23^a of the box when the bolt 24^a is inserted to the position indicated in Figure 8. After insertion, the lever means 61 may be removed releasing the spring 26^a, whereby the hinged portion 7^a of the lid is resiliently held against the upper portion 6^a thereof. After insertion, the bolt 27^a may be prevented from undesired removal by means of the hairpin cotter or the like 62.

Referring now to the embodiment of my invention illustrated in Figures 10 and 11, there is shown a portion of a side frame 1^b with a journal box 5^b comprising an integral upper portion 6^b and a removable lower portion 7^b swingingly mounted, as heretofore, at its inner edge by a bolt 18^b extending through hinging ears 19^b on the lower half 7^b of the journal box and webs 15^b on the frame. The journal box, in general, may be substantially identical with that of the first embodiment illustrated in Figures 1 to 7, inclusive. The free or swinging edge of said box, however, is provided with spaced outstanding flange or web portions 63 connected at their upper edges by a web portion 23^b forming a pocket 64 receiving resilient means 13^b for connecting said movable portion of the box to the frame.

The adjacent end of the frame 1^b is similarly formed, that is, the sides thereof are extended below the roof portion of the box and formed with inwardly extending flange or ledge portions 11^b forming abutments against which the upper end of the resilient means 13^b is adapted to engage. Said resilient means, in the present embodiment, comprises a bolt 24^b formed with a head 25^b and encircled by a spring 26^b engaging the head at its lower end and the web portion 23^b at 110 its upper end. The upper end of the bolt 24^b is threadably mounted in a socket portion 65 which, in turn, is pivoted to a link 66, the upper end of said link being connected to a tensioning lever 67 by means of a rivet or other pivotal means 68.

The manner of resiliently holding the swinging portion of the box against the upper portion, it is thought, will be clear from the foregoing but in order to avoid any possibility of misunderstanding, it might be stated that, after pivotally mounting the inner edge of the box portion 7^b by means of the bolt 18^b, the resilient means 13^b is connected thereto by inserting the bolt 24^b with the spring 26^b 130

therearound through the aperture in the web 23^b and threadably connecting the socket 65 thereto by turning said socket, the head 25^b of the bolt being prevented from turning by engagement between the webs 63. After 5 threading the bolt into the socket 65 to the desired extent, the lever 67, held in an inverted position with respect to that shown in Figure 11, is moved toward the end of 10 the frame 1^b, the link 66 being inserted in the slot formed between the ledge portions 11^b and the lip portion 69 and the lever engaging the corresponding lip portion 70 on the frame. Upon rotating the lever 67 clockwise 15 to the position shown in Figure 11, it will be apparent that the pivotal connecting means 68 is raised, correspondingly compressing the spring 26^b and holding the pivotally mounted portion 7^b of the box resiliently 20 against the fixed portion 6^b thereof, as illustrated in the drawings. When in the position illustrated, the lever 67 is prevented from release by the flat lower surfaces 71 thereof on the bifurcated pivoted end engaging the 25 corresponding upper surfaces of the ledges 11^b and resiliently held thereagainst.

Referring now to the embodiment of my invention illustrated in Figures 12 and 13, a construction very similar to that shown in 30 Figures 8 and 9 is disclosed except that the engagement between the corresponding edges of the fixed portion 6^c of the box 5^c and the swinging portion 7^c thereof corresponds more nearly with that of the first embodiment. As 35 in the embodiment illustrated in Figure 8 and 9, however, the resilient means 13^c comprises a bolt portion 24^c surrounded by a spring 26^c and provided with a nut 27^c. The nut 27^c is normally engaged between the extensions 58^c from the sides of the frame 1^c whereby 40 undesired rotation thereof is prevented. The lower end of the bolt 24^c is provided with a bifurcated head 25^c, the sides of which are provided with registering apertures receiving 45 a rivet or other pivoting means 72 to connect a link 73 therewith. Said link is preferably formed with outstanding lugs 74 at intermediate portions thereof and is adapted to extend between spaced lugs 75 on the swinging portion 7^c of the journal box with the lug portions 74 engaging therebeneath for holding 50 the spring 24^c stressed for resiliently pressing the pivoted portion 7^c of the box against the fixed portion 6^c thereof.

In order to conveniently compress the 55 spring 26^c so that the engagement between the lugs 74 and 75 can be effected, the lower end of the link 73 is preferably apertured as indicated at 76 for receiving a bar or other lever means 77, one end of which is adapted to engage a hook or other fulcrum 78 provided on the swinging portion 7^c of the journal box and the opposite end manually operated.

From the foregoing, it will be seen that, 60 in order to connect the resilient means 13^c

for resiliently holding the parts of the box together, the bolt 24^c is first inserted through the corresponding aperture in the web portion 11^c connecting the sides of the frame 1^c, the spring 26^c inserted thereover and the nut 27^c applied to the end thereof and threadably mounted thereon by turning the bolt 24^c, said nut being prevented from turning by engagement between the extensions 58^c as will be understood. When the nut has been tightened to a sufficient extent, the swinging portion 7^c of the box is moved to closed position and the apertured portion 76 of the link 73 and the hook or fulcrum portion 78 engaged by the lever means 77 to stress the spring 26^c and permit moving the link 73 until the lug portions 74 thereon engage the corresponding lugs 75 on the swinging portion of the box.

Referring now to the embodiment of my invention illustrated in Figures 14 and 15, a construction is there disclosed which is quite similar to that of the preceding embodiment in that the swinging portion 7^d of the box 5^d is held against the fixed portion 6^d thereof by resilient means 13^d involving a bolt 24^d extending through a corresponding aperture in the web 11^d connecting the sides of the frame 1^d, said bolt 24^d having mounted thereon a spring 26^d retained in place by a nut 27^d. The head 25^d of the bolt, however, is not bifurcated but merely perforated and a link 73^d connected thereto by rivet or other pivoting means 72^d, said link comprising spaced arms 74^d joined by a connecting portion providing an aperture 76^d for receiving a bar or other lever means 77^d. The link 73^d is adapted to fit over an outstanding lug 75^d on the box and the spring 26^d is stressed until engagement between the lug and link can be readily effected by inserting the lever 77^d in the aperture 76^d and corresponding pocket providing a fulcrum 78^d in the box and applying force thereto as will be understood. For preventing undesired release of the link 73^d from the lug 75^d, said lug is preferably notched as indicated at 79 and the cooperating portion of the link similarly formed.

The resilient means 13^d may be applied in a manner similar to that described in connection with the preceding embodiment but the frame 1^d is shown unprovided with extensions cooperating with the nut 27^d to prevent turning thereof so that said nut is preferably castellated, as illustrated, and provided with a retaining cotter 80. One advantage of such a construction is that the spring can be tightened by merely turning the nut 27^d without removing the link 73^d from engagement with the lug 75^d.

Referring now to the embodiment of my invention illustrated in Figures 16 and 17, a construction is there disclosed which is very similar to that shown in connection with the

embodiment illustrated in Figures 8 and 9. The journal box 5^e, as heretofore, comprises an upper portion 6^e permanently or rigidly connected to the frame 1^e and a lower portion 7^e pivotally mounted on said frame by means of a hinge pin 18^e extending through hinging ears 19^e on the lower portion of the box and web portions 15^e on the frame. The upper portion of the box comprises a lower edge portion telescopically received in pockets 55^e formed at the upper portion of the movably mounted lower portion 7^e of the box by the upper portions of the side walls thereof and the inwardly spaced flanges 54^e extending upwardly from the sloping web portions 30^e. The movably mounted lower portion 7^e of the box is substantially concentric with the associated journal (not shown) although it is not exactly so as will be apparent from a consideration of the drawings and is provided with a flattened portion 81.

The free or outer edge of the movable portion 7^e of the box is formed with ears 23^e corresponding generally with the pivoting ears 19^e and perforated for receiving a connecting pin 24^e. Said pin 24^e is received in registering apertures 82 formed in the outer portions of the side walls of the frame 1^e below the connecting web portion 11^e adapted to support resilient means 13^e for continually urging the movably mounted lower portion of the box toward the upper portion.

From a consideration of the foregoing, it will be seen that the pin 24^e provides a safety connecting means corresponding to the pivot pin 18^e for holding the movable portion of the box under the fixed portion thereof. In order to perform the double function of preventing undesired release of the pin 24^e and also resiliently hold the lower portion 7^e of the box, resilient means are mounted on the web portion 11^e of the frame, heretofore referred to, said means comprising, in the present embodiment, a helical spring 26^e directly resting on the web portion 11^e and supporting, at its upper end, a bearing block 83 formed with an aperture 84 therethrough, the lower side of which is flattened and adapted to rotatively receive a correspondingly flattened pin 85. Said pin 85 extends outwardly through slots 86 in the side walls of the frame 1^e and is rigidly connected with the arms of the U-shaped latch member 87, as illustrated. Said latch member 87 is formed with elongated pockets 88 receiving the ends of the pin 24^e and, with a connecting portion 89, normally extending below the lugs 23^e on the box.

The latch member 87 is inserted in place by compressing the spring 26^e in any desired manner as by inserting a bar or other lever means (not shown) above the connecting portion 89 of the latch into the corresponding pocket 60^e providing a fulcrum for moving said latch 87 downwardly and stressing the

spring until the ends of the pin 24^e slip into the openings 90 in the elongated pockets 88, whereupon said spring may be released to draw the latch 87 upwardly to resiliently support the ends of the pin 24^e and thereby urge the free end of the swinging portion 7^e of the box upwardly toward the fixed portion thereof. It will be appreciated that the apertures 82 in the frame 1^e are so large or elongated that they provide sufficient play for allowing the spring pressure to act upwardly and support the free end of the pivoted portion of the box.

From the foregoing description, it will be appreciated that a safety feature is provided in that the pin 24^e cannot be removed unless the spring latch 87 is unfastened and, even if the same should not be fully latched, the flattened side of the pin 85 resting against the corresponding flattened portion of the aperture 84 tends to hold the latch against the frame through the spring pressure on the corner of the flat. The bottom loop of the latch would then still retain the safety pin in position. If the spring should break, the entire latch 87 would drop straight down engaging the ends of the pin in the upper portions of the elongated pockets 88. If desired, of course, additional means for preventing undesired removal of the pin 24^e could be provided such as head on one end and cotter means on the other.

One function of all the preceding embodiments of my resiliently held lower half of the journal box is to utilize the same as a waste or lubricant retainer and, as it is hinged to the frame, it will not be necessary to use a separate cradle for the lubricating material assuming that the pivotally mounted lower portion of the box will be unfastened before the frame is jacked up for removal of the brass.

From a consideration of the foregoing description of my invention taken in connection with the accompanying drawings, it will be seen that I have devised an advantageous side frame and journal box construction which allows free and visual inspection of the condition of the journal upon merely dropping the lower portion of the box. The construction also permits the quick replacement of wheels without dismantling the truck and facilitates the removal of a split brass even though the same may become locked or wedged between the journal and box. In the foregoing construction in which the lower half of the box is shallow and preferably normally concentric with the journal, the amount of lubricating material necessary is reduced while, at the same time, said material is more efficiently used because it is prevented from dropping away from the journal yet, on account of the ribs on each side of the journal, danger of waste or the like creeping around the journal and wedging between the

same and the brass, where it would be apt to cause undue heating, is obviated. On account of the resilient means for holding the lower portion of the journal box against the upper portion, the lubricating material in said lower portion is constantly held in place against the journal regardless of wear of the same and the associated brass. Because of the telescoping or interlocking joint between the upper and lower halves of the box, dirt and other foreign material may be effectively excluded.

Having now described my invention, I claim:

1. A truck side frame provided with journal boxes at the ends thereof, said boxes being formed as upper and lower sections resiliently held together.

2. A truck side frame provided with journal boxes at the ends thereof, each of said boxes being formed as an upper section, and a lower section resiliently held against said upper section.

3. A truck side frame cast with the top portions of journal boxes integral therewith and lower portions of said boxes removably connected to said frame and adapted for being resiliently held in position against said upper sections.

4. A cast side frame formed with the roofs and upper portions of the side walls of journal boxes integral therewith, cooperating lower portions of said journal boxes pivotally mounted on said frame and adapted to be swung into or out of engagement with the upper portions of said boxes, and means holding the free ends of said journal boxes resiliently in position with respect to said integral portions.

5. A truck side frame provided with the upper portions of journal boxes connected thereto, cooperating lower portions of journal boxes movably mounted with respect to said upper portions and adapted for being held in proper relation with respect thereto, said lower portions having walls spaced from associated journals for holding lubricating material thereagainst and being formed relatively shallow for bringing such material close to said journals.

6. A truck side frame provided with journal boxes at the ends thereof, the upper halves of said boxes being formed integral with said frame and the lower halves being formed with flanges adapted to interlock with said upper halves for sealing the joint thereto, said lower halves being formed relatively shallow, and means for movably supporting the same against said upper halves.

7. A truck side frame formed with journal boxes at the ends thereof, said boxes being provided with ribs extending, from approximately the plane of the axes of the associated journals, inwardly and downwardly from the sides thereof for holding lubricating means therebeneath and maintaining it in place.

8. A truck side frame provided with journal boxes at the ends thereof, each of said boxes being formed with an upper section, and a lower section removably held in position against said upper section, said lower section being formed with ribs extending inwardly and inclined downwardly from the side walls thereof, said ribs being adapted to underlie the side walls of the upper sections and maintain lubricating material in place.

9. A truck side frame provided with journal boxes at the ends thereof, the lower portions of said boxes being normally coaxial with and spaced from an associated journal for maintaining associated lubricating material in proper relation with respect to said journal.

10. A truck side frame provided with journal boxes at the ends thereof, said boxes being formed as upper and lower sections telescopically engageable, the lower portions of said lower sections normally curving beneath and spaced from an associated journal and formed substantially coaxial therewith for maintaining lubricating material in proper position with respect thereto.

11. A truck side frame provided with journal boxes at the ends thereof, each of said boxes being formed with an upper section rigidly connected to said frame and a lower section resiliently connected to said frame in cooperative relation with respect to said upper section and adapted to contain lubricating means and constantly hold the same in place against an associated journal regardless of wear.

12. A truck side frame provided with journal boxes, each of said boxes being formed as an upper section immovably connected in place and a lower section pivotally mounted to said frame beneath said upper section, said lower section being adapted to contain lubricating material, and resilient means for urging said lower section upwardly to constantly hold said lubricating material against an associated journal regardless of the wear thereof.

13. A journal box comprising upper and lower sections, means pivoting said sections together and resilient means for urging the free edges of said sections toward each other.

14. A journal box formed of an upper section adapted for rigid connection with an associated frame, a lower section pivotally connected to said frame at one side thereof, connecting means engaging an opposite portion of said box and adjacent portion of the frame, and resilient means acting on said means and the frame to constantly urge said lower portion of the journal box into proper position with respect to the upper portion.

15. A journal box formed with upper and lower sections resiliently held together, both of said sections being provided with complementary portions of a dust guard well and

upper and lower sections of a dust guard mounted in said well, each of said sections being provided with resilient means for urging the same toward the other section.

5 16. A journal box comprising movably associated upper and lower sections, dust guard pockets provided in said sections and a dust guard mounted in said pockets; said dust guard being formed with means for 10 causing the same to snugly embrace an associated journal.
